United States Patent Office

Des. 176,232
Patented Nov. 29, 1955

176,232

AWNING

Peter M. Scatton, Philadelphia, and John P. Scatton, Hazleton, Pa., assignors to Scatton Bros. Mfg. Co., Philadelphia, Pa., a partnership

Application March 1, 1955, Serial No. 34,805

Term of patent 14 years

(Cl. D21—6)

Fig. 1.

Fig. 3.

Fig. 2.

Figure 1 is a perspective view of an awning showing our new design;

Figure 2 is a front elevational view thereof; and

Figure 3 is a side elevational view thereof, the view of the opposite side of the awning being the same.

We claim:

The ornamental design for an awning, substantially as shown and described.
